CLAIM

The ornamental design for a door facing, as shown and described.

DESCRIPTION

FIG. 1 is a front perspective view of a first embodiment of a door facing, showing our new design;

FIG. 2 is a front elevation view thereof;

FIG. 3 is a front perspective view of a second embodiment of a door facing; and,

FIG. 4 is a front elevation view thereof.

The broken lines in the drawings depict unclaimed subject matter and form no part of the claimed design.
